UNITED STATES PATENT OFFICE.

LOUIS HARRIS, OF CHICAGO, ILLINOIS.

SURFACING APPARATUS.

Specification of Letters Patent.

Patented Oct. 16, 1917.

1,243,404.

Application filed January 22, 1917. Serial No. 143,726.

To all whom it may concern:

Be it known that I, LOUIS HARRIS, a citizen of the United States, residing at Chicago, in the county of Cook and State of Illinois, have invented certain new and useful Improvements in Surfacing Apparatus, of which the following is a specification.

My invention relates to improvements in surfacing apparatus for plane or flat, preferably wooden surfaces, and has especial reference to apparatus of this character for planing and scraping the surfaces of bowling alleys.

One of the objects of my invention is to provide an apparatus, consisting of a series or gang of overlapping planes removably secured in a suitable slab or frame block, movable longitudinally of the alley, over the surfaces of such structures in paths substantially parallel with the grain of the boards or wood of which the alley is composed, whereby to prevent transversely extending kerfs, tool marks, or scratches to divert the path of the ball as when the usual rotary planer and sander is used for the purpose.

Another object of my invention is to simplify and cheapen the driving and guiding means for the planes without requiring a special track to be laid upon which to move the surfacing apparatus.

Other and further objects of my invention will become readily apparent to persons skilled in the art, from a consideration of the following description when taken in conjunction with the drawings, wherein:

Fig. 1 is a broken away plan view of a bowling alley showing my apparatus as applied thereto.

Fig. 2 is a longitudinal section taken on line 2-2 of Fig. 1.

Fig. 3 is an enlarged plan view of the plane containing block.

Fig. 4 is a further enlarged broken away portion of the plane block, showing the manner of fastening the planes and scrapers in the block.

Fig. 5 is an enlarged section taken on line 5-5 of Fig. 3 showing the plane block and one of the planes.

Fig. 6 is a similar section showing a scraper.

Fig. 7 is a detail of the plane fastening latch.

In all the views the same reference characters are employed to indicate similar parts.

My apparatus consists essentially of a

block or slab of cast iron, or the like, with a plurality or group of apertures at each end to receive removable planes arranged in interlocked relation and so positioned that when the block is being pulled or driven in one direction, one series or set of planes will be operatively active, the other series having been previously automatically raised so that their bits will not touch the surface over which they are passing, and when the block is being moved in the opposite direction the formerly idle series are depressed so as to make engagement with the underlying surface of the alley while the before-mentioned active series are raised from the surface over which the block is to be passed. It further consists in especial and improved means for dragging the block over the surface to be planed and other details of construction to be hereafter more fully explained.

10 is a block, preferably of cast iron, or similar material, containing two rows of perforations, 11 and 12, at each end, within which to contain planes 13 or scrapers 14. The perforations 11 and 12 are so arranged, as will be observed, that the bits of the planes will overlap so that the planes will jointly operate as if the cutting or planing were being done with a single blade. Each of the perforations, 11 and 12, is provided with a shoulder 14, at one end, undercut, as at 15, under which to receive a similar shoulder 16 projecting forwardly from the plane or scraper to prevent that end of the plane from rising above the plane block. The lower surface 17 of the planes is designed to be in line with the lower surface 18 of the plane block. The plane block is also provided with another shoulder 19, somewhat longer than the shoulder 14, having a depression in its face wherein to receive an open helical spring 20 which is adapted to lift the end of the plane upon which the shoulder 19 is contained, when the latch 21 is removed from its path. In other respects the plane 13 and the scraper 14 are of the usual conventional form, each having a bit 22 and 23, respectively, secured by a thumb nut 24 and a pivoted lever 25 as usual in such structures, and where I have used the term plane in the claims, it is intended to be sufficiently comprehensive to include the interchangeable scrapers.

Near the center of the plane block 10 is a cable, guiding sheave 23, mounted upon the standard 24, one on each side. These sheaves

are to guide the ropes or cables used to pull the plane block across the surface to be planed. Near each end of the plane block, and on either side thereof, are eye bolts 25 to which to secure the ends of the cables. In substantially the center of the plane block 10 is a seat 26 for accommodation of the operator who may ride upon the plane block when additional weight is necessary to hold it to the underlying surface to be planed.

An electric motor 27 is mounted upon the guide track 28. The track is held in place, at one end of the alley 29, by means of the springs 30-30 or other preferably yielding fastenings. These springs give tension to the cables 31 and 32 and hold them in close contact with the driving sheaves 40. On the motor shaft 33 is a small pinion 34 geared into a larger gear wheel 35. The gear wheel 35 is secured to a transverse shaft 36 which has bearings in a frame 37 as at 38 and 39. On the outer ends of the shaft 36 are sheaves 40-40 for the cables 31 and 32, respectively. At the other end of the alley 29, is a similar shaft 41, having bearings in standards 42-42 that are secured to a longitudinally adjustable structure or base plate 43. The standards 42-42 are separated so that the sheaves 44-44 on the shaft 41, are the same distance apart as the sheaves 40-40 on the shaft 36. The base plate 43 is slidable in a guiding casting or trackway 45 in a direction transversely of the alley 29. The casting 45 may be secured in place in any desirable manner, as by block and fall or by bolts or the like. The springs 30-30 serve to put sufficient tension on the cables 31, 32 and the sheaves 40-40 to produce the required traction to move the plane block 10 over the alley way.

The rotation of the armature of the motor 27 will cause the sheaves 40-40 to move the cables 31 and 32 in either direction, toward the motor or from it, and thereby to move the plane block 10 in corresponding directions. When the block is being moved toward the right hand side, the planes on the left end of the plane block 10 are in operative condition, the planes on the other end of the block being lifted from contact with the underlying surface to be planed.

The latches 21 which hold the planes and scrapers down to their work are connected together by rods 46 so that when the rods 46 are moved axially, all of the latches 21 of a series are moved in a given direction, either to hold the planes in their positions or to release them, whereupon the springs 20 will lift them so that the blades of the lifted planes will not be in contact with the underlying surface of the alley. The rods 46 are connected at one end to the bell cranks 48 and 49, respectively, and these bell cranks are connected together by links 50, the arrangement being such that when the link

50 is pulled on the latches 21 are thereby moved in position to compress the springs 20 and to seat the plane 13, or the scraper 15, in the plane block, as clearly shown in Figs. 5 and 6.

A bifurcated lever having arms 51, 51' is rotatable by a hand wheel 52, the arms 51, 51' being connected each to a link 49 by the rods 53 and 54. The arrangement is such that when the hand wheel 52 is turned in one direction one set of the latches 21 are moved in position to permit the springs 20 to raise the planes or scrapers, as shown on the right hand side of Fig. 3, and when they are moved in the opposite direction the latches 21 are moved to such positions as to depress the planes or scrapers against the resistance of the springs 20 to hold them in operative positions as shown in Figs. 4, 5 and 6.

Now when the plane block 10 is moving to the right, as shown by the arrow in Fig. 3, the set of the planes or scrapers on the left end of the block are depressed into operative position while the planes or scrapers on the other end of the block are raised out of contact with the underlying surface.

When the block has been moved the full extent of the alley and the motor is reversed so as to move the block in the opposite direction, then the hand wheel 52 is first turned so as to cause the latches 21 to release the planes on the left end and depress those on the right end, so that when the block 10 is being moved to the left the planes on the right or trailing end are at work.

After the block 10 has been pulled over the alley, beginning at one side thereof, the motor 27 may be moved laterally so that the block will move over to the new path and thus the motor and the counter shaft 41 may be moved in the respective guide ways 28 and 45, until the entire alley has been thus planed. After the planing operation has been completed the planes 13 are replaced by the scrapers 14 and the operation is substantially repeated.

I have not shown the electric circuits for the motor nor the means for reversing it, as such means do not constitute any part of my invention.

Having described my invention, what I claim is:

1. In a device of the character described the combination of spaced-apart parallel guide tracks, or ways to be placed at opposite ends of a surface to be planed; a structure, one for each way, carrying spaced-apart sheaves and longitudinally adjustable on said ways; a motor, for driving one pair of sheaves, movable with the respective structure, a block, carrying a plurality of planes, movable between said ways and a pair of chains, or cables overlying appropriate sheaves on said structures and having

their opposite ends connected to opposite ends of said plane block.

2. In a device of the character described the combination of spaced-apart parallel 5 guide tracks, or ways to be placed at opposite ends of a surface to be planed; a structure, one for each way, carrying spaced-apart sheaves and longitudinally adjustable on said ways; a motor for driving one pair 10 of sheaves movable with the respective structure; a block, carrying a plurality of planes, movable between said ways; a pair of chains, or cables overlying appropriate

sheaves on said structures and having their opposite ends connected to opposite ends of 15 said plane block and springs connected to one structure to increase frictional contact between the driving sheaves and the respective chains or cables.

In testimony whereof I hereunto set my 20 hand in the presence of two subscribing witnesses.

LOUIS HARRIS.

In the presence of—

STANLEY W. COOK,

MARY F. ALLEN.
